UNITED STATES PATENT OFFICE.

HORACE A. BODGE, OF BROOKLYN, NEW YORK.

CLOTHES-WRINGER.

1,356,186.

Specification of Letters Patent. Patented Oct. 19, 1920.

Application filed April 3, 1920. Serial No. 371,084.

To all whom it may concern:

Be it known that I, HORACE A. BODGE, citizen of the United States, and resident of Brooklyn, in the county of Kings and State 5 of New York, have invented certain new and useful Improvements in Clothes-Wringers, of which the following is a specification.

This invention relates to clothes wringers of the hand operated type adapted for 10 mounting on wash-tubs for wringing out the water from the cleansed clothes.

The invention has for a general object to provide an improved clothes wringer characterized by simplicity and durability 15 of construction, and by efficiency of operation.

A further object of the invention is to provide a simple device whereby the water wrung from the clothes may be directed 20 back into the tub from which the clothes were removed for wringing.

For further comprehension of the invention, and of the objects and advantages thereof, reference will be had to the following 25 description and accompanying drawings, and to the appended claims in which the various novel features of the invention are more particularly set forth:

Figure 1 of the drawing is a face view of 30 a wringer constructed according to the invention.

Fig. 2 is a transverse section on the line 2—2 of Fig. 1.

Fig. 3 is a partial vertical axial section 35 of one end of the wringer.

Fig. 4 is a fragmentary face view showing a modification.

The frame of my improved clothes wringer is preferably made mainly of metal tubing 40 and comprises a top horizontal member 1 connected at its ends by elbows 2 to the upper ends of side members 3 the lower ends of which are screwed into connections 4 and 5 the former of which is a T and the latter a cross. The lower ends of these connections have secured thereinto short tubes 6 which latter are screwed at their ends, as 45 shown in Fig. 3, into the web portions of a pair of inverted-U clips or feet 7 which are adapted to straddle the edge of a wash tub in the usual manner, and are provided with the clamping screws 8 threaded through one of the legs thereof whereby the wringer is fastened to the tub. To permit of adjustment 50 of the clamping device to fit upon the

edge of a horizontal support the opposite legs of the clips to those carrying the screws 8 are provided with tapped openings 9 into which the tubes 6 may be screwed, the clamps then assuming the position shown 60 in dotted lines in Fig. 2. The bottom horizontal member of the frame is formed by a flat strap 10 which is perforated at its ends to receive the tubes 6 and is clamped against the feet 7 by means of nuts 11 threaded on 65 the tubes and screwed down against the straps.

Within the rectangular frame thus formed are supported the rollers 12 and 13 of the wringer, the upper roller 12 being vertically 70 adjustable and the lower roller 13 being on a fixed axis. Each of these rollers comprises a facing of rubber fixed by vulcanizing or otherwise on tubes 14 and 15, these tubes extending at their ends slightly beyond the 75 ends of the roller bodies. To support the upper roller 12 a pair of sleeves 16 are slidably mounted on the upper tubes 3, these sleeves being conveniently formed of T-unions whose lateral offsets have fixed therein the pins 17 which project freely into the opposite ends of the tube 14 and so rotatably support the upper roller. This upper roller is pressed yieldingly down toward the lower roller by means of a pair of expansion 80 springs 18 coiled around the tubes above the sleeves 16 and bearing between the latter and the elbows 2, enlarged washers 19 being preferably interposed between the ends of the springs and the sleeves and elbows. 85

The lower roller 13 is mounted in place by means of a rod 20 which extends completely through the tube 15 and is riveted or otherwise secured to the ends of the tube 90 as at 21. This rod projects beyond the roller tube 15 at both ends, one end extending freely into the lateral offset of the T-union 4, while the opposite end extends freely through the horizontal elements of the cross connection 5. As will be apparent the roller 100 will be thus rotatably mounted in the frame, the ends of the rod 20 acting as trunnions for the roller.

The end of the rod 20 which projects through the cross connection is preferably bent at an approximate right angle to form a crank arm 22 for rotating the rod; the end of this arm having a handle 23 mounted thereon in any well known manner.

In order to enable the water wrung from 110

the clothes to be directed to either side as desired an adjustable baffle strip 25 is pivoted on the frame strap 10 and is adapted to be swung either to the position inclining downwardly in one direction under the rollers shown in full lines in Fig. 2 or to the position shown in dotted lines in this figure inclining downwardly in an opposite direction. As here shown this baffle strip 25 is formed on opposite ends with downwardly projecting lugs 26 which are pivoted to upwardly projecting lugs 27 on the frame strap. It will be apparent that by adjusting this baffle strip the water dripping from the rollers may be discharged to either side as desired.

In Fig. 4 I have shown a modified form of resilient pressure means applied to the upper roller 12 and comprising a bow spring 30 fixed midway between its ends to the underside of a block 31 secured on the top member 1, the ends of the spring being perforated to surround the side members 3 and pressing downwardly on the sleeves 16. Having thus described my invention what I claim as new and desire to protect by Letters Patent of the United States is as follows:

1. A clothes wringer comprising tubular top and side frame members, one of said side frame members including a T-union, the other of said side frame members including a cross connection, a pair of rollers, a rod passing through one of said rollers

and journaled in the said union and connection, the end of the rod adjacent the said cross connection projecting beyond the latter and being formed with a crank handle. 35

2. A clothes wringer comprising tubular top and side frame members, one of said side frame members including a T-union, the other of said side frame members including a cross connection, a pair of rollers, a rod passing through one of said rollers and journaled in the said union and connection, the end of the rod adjacent the said cross connection projecting beyond the latter and being formed with a crank handle, sleeves formed of T-unions slidable on said side frame members, and pins projecting 40 from the lateral offsets of said sleeves and rotatably supporting the other of said rollers. 45

3. A clothes wringer comprising tubular top and side frame members, rollers journaled in the side frame members, a pair of U-shaped clamping clips screwed upon the lower ends of said side frame members, a strap rigidly connecting said side frame members and clamped at its ends against 50 the said clips, said clips being adjustable to engage a member extending either in the general plane of the wringer or transversely thereto. 55

Signed at New York in the county of New York and State of New York this 1st day of April, A. D. 1920.

HORACE A. BODGE.
